UNITED STATES PATENT OFFICE.

CHARLES M. WHITE, OF FORT DODGE, IOWA.

HOSE REEL.

Application filed September 22, 1924. Serial No. 739,179.

To all whom it may concern:

Be it known that I, CHARLES M. WHITE, a citizen of the United States, residing at Fort Dodge, in the county of Webster and 5 State of Iowa, have invented certain new and useful Improvements in a Hose Reel, of which the following is a specification.

This invention relates to improvements in hose reels and is more particularly adapted 10 to a means for supporting a garden hose in the basement of a house or building when the same is not in use, means being further provided for securing the hose to the reel when the same is to be wound there around.

15 Another important object of the invention is to provide a hose reel of the above mentioned character, wherein the operating means therefor is disposed outside of the house or building so that it does not become 20 necessary for a person to wind the hose around the reel from the basement, thereby saving considerable time and labor.

Another important object of the invention is to provide a hose reel of the above mentioned character, which is simple in construction, inexpensive, strong and durable and furthermore adapted for the purposes 25 for which it is designated.

Other objects and advantages of this invention will become apparent during the 30 course of the following description.

In the accompanying drawing forming a part of this specification and in which like numerals designate like parts throughout the 35 same:

Figure 1 is a side elevation of my improved hose reel showing the manner in which the same is supported and further illustrating the manner in which the garden 40 hose is attached to the winding cable, and

Figure 2 is a front elevation of the reel and the supporting brackets therefor.

In the drawing wherein for the purpose 45 of illustration is shown the preferred embodiment of my invention, the numerals 1 and 2 designate a pair of supporting brackets which are secured at their upper portions to a pair of adjacent floor joists such as are shown at 3 and 4 respectively.

50 Journaled in the lower ends of the supporting brackets 1 and 2 is the shaft 5 and carried thereon is the reel or drum 6, the same being disposed between the supporting brackets and below the floor joists in the

55 manner clearly illustrated in Figure 2. A beveled gear 7 is provided on one of the

ends of the shaft 5 and the same is adapted to mesh with a similar bevel gear 8 carried by the lower end of the elongated operating rod 9 which is supported on the bracket 1 by means of the angular member 10.

The operating rod 9 extends upwardly at an angle with respect to the supporting bracket 1 and the upper portion thereof is adapted to extend through a suitable opening provided in the side wall of a building designated generally by the letter A in the manner clearly illustrated in Figure 1. A handle such as is shown at 11 is mounted on the upper end of the rod for operating the 70 same for the purposes hereinafter to be more fully described.

A cable 12 is fastened at one end to the drum or reel 6 carried by the other end thereof is the screw-threaded plug 13 which 75 is adapted to be threaded into the threaded socket or coupling 14 carried by the end of the garden hose 15 and which is usually adapted for engagement with the nozzle of the water supply pipe.

80 With the parts arranged as shown in the drawing the garden hose may be easily and readily wound around the reel or drum 6 by simply turning the handle 11 causing the rod 9 to rotate and in turn rotating the shaft 5 and the reel through the medium of the bevel gears 7 and 8 and the hose will extend through the opening 16 provided in the side of the building or house and will be wound around the drum so that the garden hose 90 will be supported on the drum between the supporting bracket when not in use. This construction furthermore enables the garden hose to be readily unreeled from the drum whenever it is desired to use the same 95 and by detaching the screw threaded plug 13 from the coupling 14, the coupling 14 may be threaded onto the water supply pipe in the usual manner.

100 The provision of a hose reel of the above mentioned character, obviates the necessity of having to carry the hose from the basement or cellar of a house when it is desirous of using the same and again having to carry the same back into the cellar after the hose has been used. The hose will furthermore 105 be supported in the basement in such a manner as not to interfere with a person walking around the cellar and will not occupy much space.

110 The simplicity in which the present device is constructed enables the same to be

easily and readily secured in position and will at all times be positive and efficient in carrying out the purposes for which the same is designated.

5 While I have shown the preferred embodiment of my invention, it is to be understood that various changes in the size, shape and arrangement of parts may be resorted to without departing from the spirit of the invention and the scope of the appended claim.

Having thus described the invention, what I claim is:—

10 A hose reel comprising a pair of supporting brackets adapted to be secured to a pair of floor joists of a building, a shaft jour-

naled between the lower ends of the brackets, a reel carried by the shaft, a cable secured at one end to said reel, means on the other end thereof for attachment to one end of 20 a hose, a beveled gear on one end of said shaft, an operating rod extending outwardly from the supporting bracket beyond the outside of the building, a beveled gear on the lower end thereof adapted to mesh with the aforementioned beveled gear, and a handle on the outer end of the rod for rotating the same whereby the reel is rotated and the hose is wound therearound.

25 In testimony whereof I affix my signature.

CHARLES M. WHITE.
